(57) CLAIM

I claim the ornamental design for a receptacle for recycled materials, as shown and described.

DESCRIPTION

FIG. 1 is a perspective view of a receptacle for recycled materials showing my new design;

FIG. 2 is a left side elevational view thereof, the right side elevational view thereof being a mirror image of the left side elevational view thereof;

FIG. 3 is a front elevational view thereof, the rear elevational view thereof being a mirror image of the front elevational thereof;

FIG. 4 is a top plan view thereof; and,

FIG. 5 is a bottom plan view thereof.

The broken lines in FIG. 1 are for illustrating unclaimed portions of the receptacle for recycled materials and form no part of the claimed design.
